(57) **CLAIM**

The ornamental design for a baton, as shown and described.

DESCRIPTION

FIG. 1 is a bottom perspective view of the baton;
FIG. 2 is a right side view of the baton, with the left side view being symmetrical to the right side view;
FIG. 3 is a top plan view of the baton; and,
FIG. 4 is a bottom plan view.
The broken line showing of the environment in the drawings is for illustrative purposes only and forms no part of the claimed design.
